HOSIERY

Mary F. Hearn, Raleigh, N. C.

Application July 24, 1934, Serial No. 736,763

5 Claims. (Cl. 2—239)

This invention relates to hosiery particularly, although not necessarily, adapted for feminine wear.

The invention primarily aims to provide a novel type of hosiery which may be worn with comfort, which will overcome wear at the toes, and which is primarily adapted for use when sandals are worn or shoes of any type are worn in which the toes or portions of the foot are exposed.

The more specific objects and advantages will in part be pointed out hereinafter and otherwise become apparent from a consideration of the description following taken in connection with accompanying drawing illustrating an operative embodiment, in which

Figure 1 is a view in perspective of the foot and lower leg portion of a stocking showing the invention, and

Figure 2 is a similar view of a modified construction.

Referring specifically to the drawing, and first to Figure 1, a stocking or article of hosiery of any desired length is shown at 10, for instance knitted or otherwise manufactured. The forward portion or toe of the stocking is cut away as shown leaving a base portion 11 extending forwardly beyond the upper portion, such base portion 11 extending forwardly under the sole of the foot and approximately to the base of the toes, while the upper portion terminates over the instep at the base of the toes.

Strips 12 are attached to the forward edge of the base portion 11 at one end, and at the other end to the forward portion of the upper of the foot of the stocking, thus providing one strip, strap or element 12 between each toe. Similar strips or straps 13 of any desired number, are secured at opposite ends to the side edges of the base 11 and are also secured to or free of the strips or straps 12, as preferred. The strips or straps 12 and 13 may be made of desired material, for instance, textile fabric. Said strips are widely separated and hence afford maximum ventilation.

In Figure 2 a modified form is shown which corresponds to that of Figure 1 except the base, here designated 11' is longer than the aforesaid base 11, and the upper portion of the foot of the stocking terminates across the instep, and a greater number of the strips or straps 13', corresponding to those at 13 are used, being fastened in place in the same manner. The stocking of Figure 2 is made of the same material as in Figure 1, and likewise the strips or straps

12' and 13' are made of the same material as those at 12 and 13.

Various changes may be resorted to provided they fall within the spirit and scope of the invention.

I claim as my invention:

1. An article of hosiery having a foot portion cut away at the toe, a base extending forwardly from the lower wall of the foot portion, flexible dividing elements for disposition between the toes extending substantially longitudinally and extending from the forward edge of said base portion and to the upper portion of said foot.

2. An article of hosiery having a foot portion cut away at the toe, a base extending forwardly from the lower wall of the foot portion, flexible dividing elements for disposition between the toes extending substantially longitudinally and extending from the forward edge of said base portion and to the upper portion of said foot, and strips disposed at substantially a right angle to the first mentioned strips connected to the side edges of said base.

3. An article of hosiery having a foot portion cut away at the toe, a base extending forwardly from the lower wall of the foot portion, flexible dividing elements for disposition between the toes extending substantially longitudinally and extending from the forward edge of said base portion and to the upper portion of said foot, and strips disposed at substantially a right angle to the first mentioned strips connected to the side edges of said base, said strips being widely spaced apart.

4. An article of hosiery having a foot portion cut away at the toe, a base extending forwardly from the lower wall of the foot portion, flexible dividing elements for disposition between the toes extending substantially longitudinally and extending from the forward edge of said base portion and to the upper portion of said foot, the forward edge of the upper part of the foot portion terminating at substantially the base line of the toes.

5. An article of hosiery having a foot portion cut away at the toe, a base extending forwardly from the lower wall of the foot portion, flexible dividing elements for disposition between the toes extending substantially longitudinally and extending from the forward edge of said base portion and to the upper portion of said foot, the forward edge of the upper part of the foot portion terminating substantially across the instep.
